UNITED STATES PATENT OFFICE.

MARSHALL B. LLOYD, OF MENOMINEE, MICHIGAN.

METHOD OF PRODUCING WOVEN REED ARTICLES.

1,243,082.

Specification of Letters Patent. Patented Oct. 16, 1917.

Application filed February 19, 1917. Serial No. 149,614.

To all whom it may concern:

Be it known that I, MARSHALL B. LLOYD, a citizen of the United States, and a resident of Menominee, Michigan, have invented a certain new, useful, and Improved Method of Producing Woven Reed Articles, of which the following is a specification.

My invention relates generally to the manufacture of woven reed articles and relates more particularly to the manufacture 10 of such reed articles as have a frame.

The reed fabric with which my invention is concerned is composed of a plurality of spaced members called stakes, which may be 15 of reed or wire, and which in workable lengths have sufficient rigidity to be self-supporting and to resist considerable forces tending to bend or kink abruptly. In this 20 respect at least they differ greatly from the loose character of the threads of cloth which can be bent, twisted or kinked in almost any manner with little force and without materially injuring them. Upon these stakes, 25 long strands called fillers are woven over some of the stakes and under others. For example, the filler strand in some instances may pass over one stake and under the next adjacent stake, or it may pass over one stake and under the next two adjacent stakes, or 30 it may vary in the manner in which it weaves under and over the stakes in a great many ways to produce different results and effects. The reed fabric with which my invention is concerned is also to be distinguished 35 from the cane fabric such as is extensively used for chair seats and the like. While the filler strands may be and sometimes are put under such tensions as will gradually curve or shape the stakes to the 40 end that the finished fabric will have the desired form, the stakes are not usually abruptly bent or displaced by the filler strands but on the other hand, the filler strands are bent and shaped to interweave 45 around the stakes.

In weaving such articles it has hitherto been customary to fasten the stakes, in spaced relation, to the article frame and then to weave the filler strands thereon, the reed 50 worker shaping the articles in the process of weaving to desired form. If the article is one that is irregular in shape, the stakes project at various angles. During the weav-

ing operation under the hitherto universal practice, these stakes must be constantly 55 shaped, positioned, and aligned so that the fabric will assume the desired shape and also will have an appearance of uniformity and particularly to the end that the stakes shall assume regular lines. The operation 60 of weaving and shaping the reed fabric upon the article frame is a most difficult one because of these many variable factors, and hence requires highly skilled workmen; so much so that where there is any amount 65 of shaping, as is necessary under present methods, in an article having pleasing curved lines, only workers having several years experience can be employed and then the time required is considerable even to 70 manufacture a relatively small article. As a result of the foregoing facts, reed articles, while extensively used, are at the present time expensive.

The general object of my invention is to 75 provide a method wherewith it shall be possible to weave reed articles, having a frame, with greater rapidity and at lower cost than has hitherto been possible.

Further objects of my invention are to 80 provide a method in which many of the hitherto variable elements or factors shall be eliminated; wherewith the personal element of the weaver shall also be largely eliminated; wherewith artistic articles having 85 curved or irregular lines can be produced with substantially the same ease as the straight uniform and simple articles; with which it shall be possible to weave the reed fabric with greater uniformity and increased strength; wherewith unskilled workers can produce reed articles of the kind hitherto producible only by skilled workmen; and wherewith the hitherto highly individualistic weaving of each reed fabric 90 upon each article frame can be reduced to a factory system of weaving the reed fabric apart from the frame in a convenient manner and in then applying the woven fabric to the frame.

My invention consists generally in the manner, steps, acts and sequence thereof, whereby the above named objects, together with others which will appear hereinafter are attainable, and my invention will be 105 more readily understood by reference to the

accompanying drawings, illustrative thereof and wherein:

Figure 1, is a bottom plan view of a portion of a templet used in the production of 5 the article of the instant case.

Fig. 2, is a side elevation of the part shown in Fig. 1.

Figs. 3 and 4, are respectively a top plan view and a side elevation of another part of 10 the templet.

Figs. 5 and 6, are respectively a top plan view and a side elevation of a still further part of the templet.

Fig. 7, is a side elevation showing the templet in assembled condition ready for the 15 weaving operation.

Fig. 8, is a fragmentary section view showing the fabric in the course of manufacture, upon the templet.

20 Fig. 9, is a cross sectional view of a portion of the fabric.

Fig. 10, is a side elevation of the finished fabric.

Fig. 11, is a perspective view of a frame 25 upon which the fabric can be placed; and

Fig. 12, is a transverse vertical section illustrating the assembled condition of the fabric and frame.

For the purposes of illustration, I have 30 chosen to depict the manufacture of a reed article of the typical jardinière shape; *i.e.*, of circular cross section and having curved or swelled side portions, because such articles on the one hand fairly illustrate the difficulty encountered in the production of reed articles under the hitherto universal method and on the other hand, the ease and simplicity of manufacturing articles under my method.

35 40 In the drawings, 1, illustrates the article frame which, in this instance, comprises an upper circular member 2, a smaller lower circular member 3, and a plurality of connecting members 4, extending therebetween.

45 The frame, in this instance, is not of the shape desired in the article and it is seldom in practice that the frame need follow closely the contour desired in the finished article. The frame in some instances fol-

50 lows the contour to some extent and in some places, but the frame is usually composed of a relatively few members which do not serve adequately as a guide to the reed workers. Under the former method, the stakes were

55 secured to the frame in spaced relation along the bottom member 3. In order to secure the bowed or curved shape in the fabric as is best illustrated in Figs. 13 and 15, it has been necessary to fasten the stakes into the

60 side portion of the frame so that they project substantially at right angles thereto. The reed worker, having fastened the stakes in this position, starts at the bottom and weaves the filler strands over and under the

65 stakes at the same time shaping the stakes

upwardly and placing the filler strands under just the right tension so that the stakes can be gradually turned from their right-angular positions progressively upward. To shape these divergent stakes gradually upward, to maintain them in proper spaced relation, and to shape the filler strand with just the degree of tension necessary to give the desired shape and character to the fabric is difficult indeed because of the many variable factors which must be considered and for which compensation must be made.

I might also state that in weaving reed in any form which is circular, spherical, or partially so, there is a natural tendency for 70 the reed to form in, that is to contract beyond the desired form or shape. This is probably due to the fact that the stakes are held at one end in desired alinement and when so secured, cannot possibly move outwardly, while the other ends of the stakes are free and under the tension necessary to secure a tight weave are gradually and naturally pulled in by the weave of the filler strand thereon. That is to say a novice 75 weaving the reed fabric could not weave it properly in such form, it requiring skilled weavers who understand thoroughly the action of the reed and who can counteract the apparently natural forming of the reed fabric to the extent necessary to give the fabric the desired shape.

I have solved this difficult complex problem in a very simple way by eliminating many of the variable factors and reducing 80 the remaining ones to simple, easily understood and easily manipulated steps. To this end instead of weaving the fabric upon the article frame which is seldom adapted for convenient weaving, I weave the fabric independent of the article frame in a manner convenient for the weaving operation and then apply the finished woven fabric to and secure it upon the article frame. As will be 85 understood shortly, in this way, I secure 90 freedom of movement and convenience in weaving which largely eliminate the present difficulty. Again I grip, space and hold the stakes in such a way and in relation to a mechanical guide, templet or form, so that 95 the most unskilled worker can weave the fabric by simply weaving in a natural manner around or against the templet or form, the templet being of such shape that the fabric produced thereon will fit the desired 100 frame, but the templet or form need not be and generally is not, of the same shape as the article frame, being designed particularly to facilitate the weaving operation and corresponding only in its general essential 105 dimensions to the dimensions of the article frame.

While my method is not to be considered limited to the manufacture of the fabric, about a templet, except where so limited in 110

- the claims, I shall describe my invention with reference to the manufacture of the fabric about a templet because this is often the preferable mode of procedure, inasmuch as unskilled workers can be more readily employed or in any event, the articles produced will be of more uniform size and shape than when produced without a templet.
- 10 In the drawings 5, represents a suitable templet upon which I weave the fabric and which, in this instance, comprises an upper or crown member 6, a segmental intermediate portion 7, and a lower or bottom part 8.
- 15 As is well shown in Fig. 7, the part 7, rests upon the part 8, and the part 6, upon the part 7. The part 7, is composed of a plurality of sections 10, and a plurality of inter-fitting sections 11, each of which carries a plurality of spaced flange-like members 12. When the sections are assembled, as is well shown in Figs. 3, 4, and 7, the members 12, form a plurality of circular plates. As the article desired has a curved or bowed side, 20 the size and relation of the members 12, is such that a line connecting their peripheries is curved or bowed. The member 7, is provided with dowels 13, to enter the holes provided therefor in the member 6. The parts 25 6 and 7, may be thus readily and accurately assembled and demounted. The crown member 6, is provided with a flaring outer face 6' to give the proper flared shape to the upper part of the fabric. The bottom 8 in 30 this instance, comprises a plate 20, having a beveled side face or edge 20', upon which is mounted a cross 21, having sides which flare to an extent necessary to form a support for all of the sections of the intermediate portion 7, as is well shown in Fig. 7. The segments 10 and 11, of the member 7, 35 may be provided with holes 23, for the reception of small alining dowels 24, on the bottom 8. Thus it becomes evident that the various parts of the templet can be readily assembled and dismounted. The stakes are fastened in spaced relation around the face 20' of the base portion and it is then a very simple operation for the reed worker to 40 weave the filler strand upon the stake in this condition, it being but necessary to continue the filler strand or strands over and under the stakes and around the templet in regular courses from the bottom to the top 45 or from the top to the bottom, although I find it more convenient to work from the bottom upwardly. The filler strands are pulled so that the stakes just follow the contour of the templet substantially as 50 shown in Fig. 8. The templet, therefore, so limits the movement of the stake and the tension upon the filler strands that the fabric is naturally shaped to the form of the templet. The relatively close relation 55 of the templet parts prevent the stakes from being bent in beyond the desired point or line. The initial position of the stakes is shown by the dot and dash lines in Fig. 7, and the final position by the dotted lines. In this manner, an endless fabric having 60 70 uniform courses of the filler strand and the desired shape can be produced rapidly by even an unskilled worker. The fabric is shown in Fig. 10, in side elevation wherein 75 35, are the stakes and 36, the filler strands. In this instance I have left portions 17, of the stakes projecting from the body of the fabric at each end. These may be laid down to form a finished edge in the usual or desired manner and either before or after the 80 fabric is mounted on the frame. Having thus produced a reed fabric of the desired size, I place it over the frame and secure the frame thereto as indicated in Fig. 12. It should be noted that the frame is a relatively simple structure, and is not of a shape such as would enable the weaver conveniently to manufacture the article shown. All that the frame is needed for is to give sufficient rigidity to the article and any unnecessary shaping is an added expense. I can use the simplest and cheapest possible frame construction as it need not be formed or shaped, unless desired, to the form or 85 shape of the fabric. 90
- 95 After the reed fabric has been woven upon the templet it will be noted that the templet is disassembled in order to free the fabric. This can be readily done by simply lifting part 6, from the part 7. The sections 11, of the part 7, can then be readily removed and thereafter the sections 10, at which time the base portion 8, can be freely withdrawn.
- 100 In qualifying the fabric or its elements as "reed" in the specification or claims, I mean to limit my invention to fabric, the elements of which coöperate in the manner above described as characteristic of the stake and strand fabric made of reed, but to embrace such materials whether they be natural reed, paper reed, or other materials having the general characteristics of reed. 105
- 110 For different articles it will be understood that templets, forms or mechanical guides of different sizes, shapes and character may be employed but my method will be found to be characterized by weaving the reed fabric in a manner convenient for the weaving operation and independent of the frame 115 and then applying the fabric to and securing it upon the frame as distinguished from the hitherto universal practice of weaving the fabric and shaping upon the frame during the weaving operation, and the herein 120 described method is cited simply as an illustration of that method.
- 125 Inasmuch as this disclosure will readily suggest to others skilled in the art to which this appertains, various methods whereby 130

the substantial objects of my invention can be attained, I do not wish to be limited to the specific stated manner of procedure nor to the precise steps, acts or stated sequence 5 thereof, except only as may be necessary by limitations in the hereunto appended claims.

I claim:—

1. The method of producing reed articles having a frame and a reed fabric which 10 consists in providing a skeleton frame having spaced connected members presenting relatively small contacting surfaces to the fabric, weaving the reed fabric independent of the frame and then placing the woven 15 fabric over and securing it to the frame.

2. The method of producing reed articles having a frame and a reed fabric of endless cross section which consists in providing a skeleton frame having spaced connected 20 members presenting relatively small contacting surfaces to the fabric, weaving the reed fabric independent of the frame to endless cross section, and then placing the woven fabric over and securing it to the 25 frame.

3. The method of producing reed articles having a frame and a differently shaped reed fabric which consists in providing a skeleton frame having spaced connected 30 members presenting relatively small contacting surfaces to the fabric, weaving a differently shaped fabric independent of the frame and then placing the woven fabric over and securing it to the frame.

4. The method of producing reed articles having a frame and a reed fabric with a bulged surface at least in part, which consists in providing a skeleton frame having spaced connected members presenting relatively small contacting surfaces to the fabric, weaving the reed fabric independent of the frame with a surface bulged out from 40

the general contour of the frame at least in part and then placing the woven fabric over and securing it to the frame. 45

5. The method of producing a reed article having a frame and a reed fabric of different cross sectional dimensions which consists in providing a skeleton frame having spaced connected members presenting relatively small contacting surfaces to the fabric, weaving the reed fabric independent of the frame with different cross sectional dimensions, and then placing the woven fabric over and securing it to the frame. 50 55

6. The method of manufacturing reed articles having a skeleton frame composed of spaced connected members presenting relatively small contacting surfaces to the fabric which consists in weaving the fabric independent of the frame about a sectional templet, in a form to inclose the templet at least in part removing, sectionally, parts of the templet to free the fabric and then placing the woven fabric over and securing 60 it to the frame. 65

7. The method of producing reed articles having a frame and a reed fabric which consists in providing a skeleton frame having spaced connected members presenting relatively small contacting surfaces to the fabric, weaving the fabric independent of the frame about a templet of proper proportions relative to the frame, and then placing the woven fabric over and securing 70 75 it to the frame.

In testimony whereof, I have hereunto set my hand, this 7th day of February, 1917, in the presence of two subscribing witnesses.

MARSHALL B. LLOYD.
